Primary Examiner — Ricky Pham(74) *Attorney, Agent, or Firm* — Hubert W. Pfabe(57) **CLAIM**

I claim the ornamental design of a handle for a utensil, as shown and described.

DESCRIPTION

FIG. 1 shows a front view of the handle of the present disclosure, in an environment showing a bottle opener;

FIG. 2 shows an alternate front view of the handle of FIG. 1, in an environment showing a bottle opener;

FIG. 3 shows a back view of the handles of FIGS. 1 and 2, in an environment showing a bottle opener;

FIG. 4 shows a side view of the handles of FIGS. 1 and 2, in an environment showing a bottle opener;

FIG. 5 shows a bottom view of the handles of FIGS. 1 and 2, in an environment showing a bottle opener;

FIG. 6 shows an isometric view of the handle of FIG. 1, in an environment showing a bottle opener; and,

FIG. 7 shows an isometric view of the handle of FIG. 1. Portions of the structure shown in FIGS. 1 to 6 with broken lines represent exemplary environments in which the claimed design may be used and do not form part of the claimed design.
